UNITED STATES PATENT OFFICE

PAUL P. SOSINSKI, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

SYSTEM OF POWER SUPPLY

Application filed June 23, 1931. Serial No. 546,227.

My invention relates to systems of power supply and more particularly to a system in which energy applied to the primary winding of an electromagnetic device causes power to be supplied from a secondary winding on said device through a contact controlled by the primary winding.

One object of my invention is to provide a novel and improved power supply device combining the functions of a transformer and relay in which the relay elements do not interfere to a noticeable extent with the production of high efficiency and favorable regulation in the transformer.

15 A system of power supply embodying my invention is particularly suitable for supplying energy to light signals or highway crossing signals in which it is of prime importance that at certain times the signals remain 20 lighted without noticeable interruption, irrespective of the continuity of the normal energy supply.

Other objects and advantages will appear from the description which follows.

25 I will describe two forms of a system of power supply embodying my invention, and will then point out the novel features thereof in claims.

In the accompanying drawing, Fig. 1 is a 30 diagrammatic view, partly in section, showing one form of a system of power supply embodying my invention. Fig. 2 is a perspective view, partly in section showing another form of a system of power supply, also 35 embodying my invention. Fig. 3 is a wiring diagram showing the electrical connections of the device of Fig. 1 or Fig. 2 applied to a load circuit consisting of a lamp and having a direct current source of energy in reserve.

40 Referring first to Fig. 1 of the drawing, the transformer relay shown therein, comprises a laminated core structure 1 of magnetizable material on which are mounted the usual primary and secondary windings 2 and 3, respectively. Coacting with the core 1 is a laminated magnetizable armature 4 pivoted upon a fixed pin 5, engaged by armature slot 10.

The armature 4 carries a block of insulating material 7 to which is attached, by means 50 of two screws, one of which is shown at 9, a

pair of contact fingers, one of which can be seen at 8^a. Each of the two contact fingers cooperates with two fixed contact posts, those for contact finger 8^a being shown at 11^a and 12^a, respectively. The armature 4 is equipped with conducting non-magnetizable bands or ferrules 6 fastened by a pin 13, which split-phase the air gap flux in well known manner to eliminate chatter of the armature, and which also serve to provide an air gap between the core 1 and armature 4. This air gap is desirable in order that armature 4 will release in spite of any residual flux which might remain after primary winding 2 is deenergized. Armature bearing slot 10 is so designed that a slight clearance exists between the top of bearing pin 5 and slot 10 with the armature in the energized position, as shown in the drawing. This "floating" bearing construction permits the armature to seat itself upon the core and makes quiet operation of the armature more easily obtainable. Contact finger 8^a coacting with contact post 12^a serves as a stop to limit the downward movement of the armature in the deenergized position.

The operation of the transformer relay shown in Fig. 1 can be understood to best advantage by referring to the wiring diagram, Fig. 3. When an alternating current source of energy is applied across terminals 17 and 18 of primary winding 2, core 1 becomes magnetized and armature 4 is attracted to the closed position shown in Fig. 1, in which position contacts 8^a-11^a and 8^b-11^b become closed. A transformer voltage will appear by induction across terminals 19 and 20 of secondary winding 3 and a circuit will then exist for load L which may be traced from one terminal 19 of secondary winding 3, wire 21, contact 8^a-11^a, wire 22, load L, wire 23, contact 8^b-11^b and wire 24 to the other terminal 20 of secondary winding 3. Load L may be any electrical load, being shown in Fig. 3 as a signal lamp.

When primary winding 2 becomes deenergized, caused by a power failure for example, armature 4 will release, opening contacts 8^a-11^a and 8^b-11^b, and closing contacts 8^a-12^a and 8^b-12^b. The deenergization of

winding 2 transfers load L to an auxiliary source such as a battery B, and a circuit is established for load L which may be traced from the positive terminal of battery B, wire 5 25, contact 8^a—12^a, wire 22, load L, wire 23, contact 8^b—12^b, and wire 26 to the negative terminal of battery B.

Referring to Fig. 2, the transformer relay structure shown therein operates in the same 10 manner as the transformer relay illustrated in Fig. 1, the difference being that in Fig. 2 an entirely separate transformer core 14 is used which is separated from an independent relay core 16 by a non-magnetizable spacer 15 15. The windings 2 and 3 are, however, common to both transformer and relay cores, as in Fig. 1. The structure of Fig. 2 is somewhat more efficient electrically and has certain manufacturing advantages over the 20 structure of Fig. 1.

Referring to Fig. 1, it is to be noted that the core 1 has been so designed that the flux set up by primary winding 2 has two flux paths, one of which in the upper portion of 25 the core, comprising the major portion of the transformer flux, is completely closed. The other flux path in the lower portion of the core includes an air gap and is threaded by the relay flux which operates armature 4.

30 One advantage of providing a closed path for a large part of the transformer flux is that a transformer having low magnetizing current and relatively high efficiency results therefrom. Another advantage is that since 35 the relay armature must carry but a small portion of the total flux set up by the primary winding, it can be made to have a correspondingly small iron section, decreasing wear which results from the hammer blow of a 40 heavy armature impinging on the core.

A further advantage is that the ferrules on the armature are linked by a small portion only of the total flux set up by the primary winding with a resultant decrease in copper 45 loss and increase in overall efficiency of the transformer relay.

The above advantages combine to produce 50 an automatic power supply and power transfer device which is both compact mechanically and electrically efficient.

Although I have herein shown and described only two forms of a system of power supply embodying my invention, it is understood that various changes and modifications 55 may be made therein within the scope of the appended claims without departing from the spirit and scope of my invention.

Having thus described my invention, what I claim is:

60 1. In combination in a transformer, a closed magnetic structure, a divided magnetic structure, a primary and a secondary winding common to both structures, and a short-circuited winding on said divided magnetic structure for phase splitting a portion of the

flux therein whereby upon energization of said primary winding the parts of said divided structure are continuously held in intimate contact.

2. A transformer comprising a closed magnetic structure and a divided magnetic structure having a plurality of relatively movable parts, a primary and a secondary winding common to both structures, and means associated with said divided structure whereby upon energization of the primary winding said parts are continuously held in intimate contact. 70 75

3. A transformer comprising a closed magnetic structure and a divided magnetic structure having a plurality of relatively movable parts, means whereby the flux in said closed magnetic structure is prevented from entering said divided magnetic structure, a primary and a secondary winding common to both structures, and means associated with 80 85 said divided structure whereby upon energization of the primary winding said parts are continuously held in intimate contact.

In testimony whereof I affix my signature. 90
